(57) **CLAIM**

The ornamental design for a shampoo sink with chair, as shown and described.

DESCRIPTION

FIG. 1 is a front and side perspective view of a shampoo sink with chair showing our new design;

FIG. 2 is a rear and side perspective view thereof;

FIG. 3 is a front elevation view thereof;

FIG. 4 is a rear elevation view thereof;

FIG. 5 is a side elevation view, the opposite side being a mirror image thereof;

FIG. 6 is a bottom plan view thereof; and,

FIG. 7 is a top plan view thereof.

The broken lines showing interior portions of the sink bowl and bottom portions of the chair are included for the purpose of illustrating a portion of the shampoo sink with chair that forms no part of the claimed design.
